CLAIM

The ornamental design for a speaker, as shown and described.

DESCRIPTION

The patent or application file contains at least one drawing executed in color. Copies of this patent or patent application publication with color drawing(s) will be provided by the Office upon request and payment of the necessary fee.

1. Speaker

1.1 : Top, front, right-side perspective

1.2 : Bottom, back, left-side perspective

1.3 : Front

1.4 : Back

1.5 : Left

1.6 : Right

1.7 : Top

1.8 : Bottom

1.9 : Reference

1.10 : Reference

Reproduction 1.9 shows a state of the claimed design being positioned horizontally; reproduction 1.10 shows a state of the cover disassembled from the body in which a built-in LED lighting is provided and forms no part of the claimed design; the broken lines shown in the reproductions depict portions of the Speaker that form no part of the claimed design; the shading lines are used to show the surface of the claimed design and do not represent its surface ornamentation.

1 Claim, 10 Drawing Sheets
